(57) **CLAIM**

The ornamental design for a car expansion bracket for mobile phone, as shown and described.

DESCRIPTION

FIG. 1 is a front, right and top perspective view of a car expansion bracket for mobile phone, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right and top perspective view of the car expansion bracket for mobile phone of FIG. 1, shown in an environment of use with a phone holder.

The broken lines depict portions of the car expansion bracket for mobile phone that form no part of the claimed design. Additional broken lines in FIG. 9 illustrate environmental subject matter and form no part of the claimed design.
